[57] **CLAIM**

The ornamental design for a archery accessory, as shown and described.

DESCRIPTION

FIG. 1 is an isometric view of the archery accessory; FIG. 2 is a front elevational view of the archery accessory; FIG. 3 is a right elevational view of the archery accessory; FIG. 4 is a rear elevational view of the archery accessory; FIG. 5 is a left elevational view of the archery accessory; FIG. 6 is a top or bottom plan view of the archery accessory, the top and bottom views being mirror images of each other; and,

FIG. 7 is an isometric view showing the archery accessory in a typical operating environment.

The broken line showing of bowstrings, an arrow and riser, in FIG. 7, is for illustrative purposes only and forms no part of the claimed design.
